WITNESS:

Joseph Carini INVENTOR
BY Victor J. Evans

ATTORNEY

UNITED STATES PATENT OFFICE.

JOSEPH CARINI, OF OLD FORGE, PENNSYLVANIA.

WAX-APPLYING MACHINE.

Application filed June 4, 1927. Serial No. 196,513.

This invention relates to a wax supplying device for the buffer rollers of shoe finishing machines, the general object of the invention being to provide means operated by a foot pedal for pressing a block of wax against the roller, thereby saving time and material and producing much better work than when the wax is applied by hand.

Another object of the invention is to so construct and arrange the device that it can be attached to any type of shoe finishing machine and when attached, it will be out of the way and will occupy but little space.

A still further object of the invention is to provide means whereby a new block of wax can be easily and quickly substituted for the old one.

This invention also consists in certain other features of construction and in the combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:

30 Figure 1 is a side view showing the invention in use.

Figure 2 is a rear view of the device itself.

Figure 3 is a section on line 3—3 of Figure 2.

35 Figure 4 is a section on line 4—4 of Figure 1.

Figure 5 is a plan view of the sector member.

40 Figure 6 is a view of the shaft which carries said member.

Figure 7 is a view of a block of wax, showing how the backing member is attached thereto.

45 Figure 8 is a rear view of the block, with a part of the covering sheet on the backing sheet broken away.

50 Figures 9, 11 and 13 are diagrammatic plan views, showing how the parts of the device are arranged when used with various shapes of buffer rollers.

Figures 10, 12 and 14 are sectional views of the blocks of wax, with the casings shown in Figures 9, 11 and 13.

55 In these drawings, 1 indicates a casing for containing a block of wax A, said casing

having its ends and bottom open, with the bottom closed by a door 2 which is hingedly connected with the rear of the casing and is held in closed position by the thumb nuts 3 on the bolts 4 which are connected with the sides of the casing adjacent the front thereof. This door permits a block of wax to be placed in the casing, as will be understood. The sides of the casing are each provided with a horizontal slot 5 and each side may be provided with the openings 6 for exposing portions of the block.

The top of the casing is provided with the slotted uprights 7 which slidably engage depending parts of the bracket 8 which may be bolted to the work shelf B of the finishing machine, the casing being held in adjusted position on the bracket by the screws 9 which pass through the slots in the uprights 7.

75 A follower plate 10 is fastened to the rear end of the block A by the pin 11 engaging the eye or staple 12 at the rear end of the block and which passes through a hole in the follower plate. A bolt 13 is attached to each side of the follower plate and these bolts pass through the slots 5 so that the follower plate is slidably supported in the casing. A shaft 14 is journaled in the upstanding ears 15 connected with the upper edges of the sides of the casing and an arm 16 is connected to each end of the shaft. The lower ends of these arms are slotted, as shown at 17, the bolts 13 passing through these slots. Anti-friction means 18, in the form of small rolls, may be placed on the bolts to engage the walls of the slots and washers 19 may be used to space the arms from the sides of the casing.

80 A sector member 20 is connected to one end of the shaft and is formed with curved guiding tongues 21 on its curved edge to form guiding means for a belt 22 which has one end connected with one end of the member 20 and its other end passes through a guide 23 carried by the opposite end of the member 22 and then said belt is connected to a spring 24 which is connected to a wire 25 by an adjusting link 26, the wire being connected to a pedal 27 which is hinged to a plate 28 which is adapted to be fastened to a floor or other support. A coil spring 29 is arranged on the central part of the shaft 14 and has one end connected with the shaft and the other to a part of the casing and this spring tends to hold the parts

105

110

with the arms holding the bolts in the rear ends of the slots 5 and the flexible connection between the member 20 and the pedal 27 in a position with the pedal raised. When the 5 pedal is depressed, the shaft will be rocked through the flexible connection from the pedal to the member 20 and said member and this movement of the shaft will swing the arm 16 forwardly so that the follower 10 plate will be moved toward the front end of the casing and thus force the block of wax against the buffer roller C so that the same will be supplied with wax. When the 15 pedal is released, the spring 29 will return the parts to normal position.

An arm 30, having a ratchet slot 31 therein, is pivoted at its rear end to one side of the casing, as shown at 32, and a spring 33 on the pivot pin tends to hold the arm in 20 lowered position. A pin 34 on one of the arms 16 extends through the slot 31 and this pin will work in the rear part of the slot as the parts are actuated to move the block forwardly. When the block has worn 25 to an extent that will permit the arms 16 to move forwardly a distance where the pin 34 will come below the second notch in the top wall of the slot 31, the spring 33 will depress the arm 30 and thus cause the pin 30 34 to enter this second notch and thus prevent the arms from engaging the rear notch in arm 30. Thus the rearward limit of movement of the arms and the follower plate is automatically advanced as the front end 35 of the block wears, so that it is not necessary to move the parts the full distance when the block is of little length.

The front end of the door 2 is extended so that it will catch any wax dropping from 40 the front end of the block due to the heating of the block through friction thereof with the buffer wheel.

A backing sheet 35 is fastened to the reduced rear end of each block of wax A by 45 means of the threads 36 which are passed through holes formed in the backing sheet and have their frayed ends embedded in the wax. A covering sheet 37 is placed over the backing sheet and this covering sheet may 50 contain directions for placing the block in the device.

Figure 9 shows a casing 1' for use with a tapered shape of buffer, as shown at C'. The block used in this casing is shown at 55 A'. As will be seen, the follower plate 10' is shaped to conform to the rear end of this block A'.

Figure 11 shows a form of casing 1" for use with a buffer C" which has a rounded 60 circumference, and Figure 12 shows the wax block A" which is used with this form of casing.

Figure 13 shows a form of casing 1' used with a buffer C' having a flat periphery 65 and Figure 14 shows the block A' used with

this form of casing. Figures 11 and 13 show the form of follower plate used with these casings.

From the foregoing it will be seen that with this device it is simply necessary to 70 depress the pedal with the foot to cause the parts to move the wax block against the buffer and when the buffer has been sufficiently waxed, the foot is removed and the spring 29 returns the parts to normal position, this normal position being automatically advanced by the arm 30, as before described.

When a new block is to be put in the casing, it is simply necessary to open the door 2 80 and pull the pin 11 from the eye 12, the arm 30 being first raised by its knob 30' to permit the follower plate and the arms 16 to be moved rearwardly. This will permit the old block to be taken from the 85 casing and a new block substituted therefor. The new block is fastened to the follower plate by the pin 11 and then the door 2 is closed. The device is then ready for operation again.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A waxing device for a shoe finishing machine comprising a casing adapted to hold a block of wax, means for connecting the casing to a part of the machine, a rock shaft journaled in a part of the casing, arms connected with the shaft, a follower plate 100 in the casing moved by the arms, spring means for holding the parts in their rearward position, pedal operated means for rocking the shaft to cause the arms to move the follower plate forwardly to feed the 105 block of wax against the buffer roll of the machine and means for automatically advancing the rear limit of movement of the parts as the block is consumed.

2. A waxing device of the class described comprising a supporting bracket, a wax holding casing vertically adjustable thereon, a follower plate in the casing, projections on the sides of the plate, the casing having horizontal slots in its sides through which the projections pass, a rock shaft journaled in the casing, arms connected therewith and having slots therein for receiving the projections, pedal operated means for rocking the shaft, a spring pressed arm pivoted to the casing and having a ratchet slot therein, a pin on one of the arms engaging the slot for automatically advancing the rear limit of movement of the parts as the wax in the casing is consumed.

3. A device of the class described comprising a casing for holding a block of wax, supporting means for the same, a door for closing the bottom of the casing, a follower plate, means for detachably connecting it to the block of wax, a rock shaft, means for causing the rocking movement of the shaft to move the follower plate, a foot pedal and flexible and adjustable means for connecting the same to the rock shaft.

4. A device of the class described com-

prising a casing containing a block of wax, a backing sheet, threads connecting the same to the block, an eye member carried by the backing sheet, a follower plate in the casing, a pin carried thereby and adapted to engage the eye in the sheet to connect the follower plate with the block of wax and manually operated feeding means for causing the follower plate to move the block in the casing.

In testimony whereof I affix my signature.

JOSEPH CARINI.
